SELF-SUPPORTING HOSIERY

William L. Thompson, Indianapolis, Ind., assignor to Real Silk Hosiery Mills, Inc., Indianapolis, Ind., a Corporation of Indiana

Application November 8, 1930. Serial No. 494,401

12 Claims. (Cl. 2—240)

This invention relates to hosiery and has particular reference to an article of such character which will be easily retained in proper position on the leg of the wearer without requiring the use of separate supporting devices such as garters.

It has heretofore been the general practice to employ garters or similar articles for retaining hosiery in place on the leg of the wearer. Aside from the annoyance of having to connect such devices with the hosiery, they have the disadvantage of making holes, stretching the stocking welt, and binding the leg in such manner as to interfere with the proper circulation of the blood. 15 I am aware that various expedients have hitherto been resorted to in order to combine supporting means with hosiery with the view of overcoming the various disadvantages such as above enumerated of separate supporting means, but 20 for the most part such structures have been unsatisfactory and inefficient. More particularly, such devices have been generally so constructed as to produce a strain on the welt of the stocking which eventuates in an undesirable 25 stretching tending to permanently unshape the welt and in some cases cause tearing.

It is the broad purpose of this invention to provide a supporting means integrally united with a stocking serving to efficiently hold the stocking in place on the leg of the wearer without strain on the welt or other portions of the structure, and exerting only a minimum of pressure on the leg, and this only in such portions as will not interfere with the circulation of the blood or 35 in other ways prove detrimental to health.

Briefly stated, my invention contemplates the association with a stocking of an elastic band serving as the tension means to retain the stocking in position on the leg, which extends only a 40 portion of the way around the circumference thereof and positioned so as to be most comfortable to the wearer, and an adjustable inelastic strap or similar device extending the remainder of the way around the circumference, adapted to 45 prevent strain on or stretching of the stocking fabric by the elastic band, and serving further to cause the elastic tensioning means to operate efficiently whatever the circumference of the leg upon which the stocking is to be supported. I 50 have found it convenient to incorporate the elastic band in a knit-in double welt at the top of the stocking, such knit-in welt having the advantage of being as elastic as other portions of the stocking and hence permitting the elastic band to operate efficiently. In order that the

tensioning device may operate with a minimum of pressure, I further propose to regulate the length of the stocking leg, preferably in accordance with the foot size, so that the top or welt will extend above the largest portion of the calf 60 of the wearer.

In order that the tensioning means which serves to support the stocking may be most efficiently associated therewith, I prefer to provide a double turned-over welt, the edge of which 65 is knit-in integrally with the top of a stocking. Such a construction has the advantage of enabling the top or welt to be made to conform to the actual shape of the calf and insures a greater degree of comfort than is obtained by a sewed 70 welt. More particularly, by reason of the fact that the knit-in welt will readily stretch as the other portion of the stocking leg, the tensioning means will operate more efficiently and will readily stretch or contract without causing a tensioning or bunching of the welt. Also, the knit-in 75 welt has the advantage of longer wear than the sewed welt which after frequent washing is likely to pull out and thus allow the tensioning means to become exposed or pulled out of the 80 stocking.

The tensioning means adapted to hold the stocking in position is preferably incorporated in the welt and comprises a rubber elastic of a type such as will not lose its elastic qualities by reason of contact with water during washing of the stocking. For most efficient results, the elastic is incorporated in the welt formed in the course of knitting and anchored in proper position as hereafter to be described so as to conform to the 90 circumference of the welt without causing any bulkiness or bunching in the fabric.

In order to avoid interference with the circulation of the blood which ordinarily results from the use of tensioning means extending entirely 95 around the circumference of the stocking or the usual separate garter, it is contemplated to have the elastic incorporated in the welt extend only a portion of the way around the circumference of the stocking top. Preferably, the elastic portion should extend around the front edge of the stocking for, say, substantially one-half of the circumference so as to exert pressure only on the bony front part of the leg. Such an arrangement results in the obvious advantage of enabling 100 the stocking to be supported in place without danger of the rubber elastic drawing the flesh and further prevents pressure on the soft rear part of the leg which might interfere with the circulation of the blood. Only the ends of the elas- 110

tic tensioning means are anchored, as by stitching, so that the main portion thereof may expand and contract freely in the welt without causing bunching or undue stretching thereof.

5 To insure proper adjustment of the tensioning means in conformity with the circumference of any size leg, and for the further purpose of preventing any strain upon the fabric in the welt, I provide an adjustable inelastic strap or the like, the ends of which are connected to the welt at or 10 near points where the elastic band terminates, such strap being intended to extend around that portion of the circumference of the stocking top lying opposite to the tensioning means. As just stated, such strap acts as a reinforcement for the 15 welt of the stocking so as to prevent any strain on the same which might otherwise result due to the utilization of the elastic around the other portion of the circumference. By making such 20 means adjustable a convenient expedient is provided whereby the proper tensioning of the elastic for any size leg may be provided so that the stocking may be held in place without undue pressure. Such strap may also be arranged as to 25 be separable at at least one point with a view of allowing the stocking to be readily put on or removed from the leg.

To further insure the proper support of the stocking with the minimum of pressure against 30 the leg, it is desirable that the leg of the stocking be sufficiently long to extend above the largest part of the calf so that the supporting means above described will be positioned to effectively 35 operate against the smaller part of the leg above the enlarged portion of the calf with the obvious result that but little tensioning will be required to keep the stocking from slipping down. I have found that the length of the stocking leg may be 40 conveniently determined in accordance with the foot size. Thus, the larger the foot size the longer the stocking leg.

A practical embodiment of my invention embodying the above-described features is represented in the accompanying drawing forming a 45 part of this specification. It will be understood that the proportions and positions of the various means combining to constitute the present invention may be altered at will without departing from the spirit and scope thereof.

50 Fig. 1 shows stockings embodying my supporting feature in position on the legs of a human;

Fig. 2 is a perspective view partly in section of the top of a stocking with the supporting means constituting this invention applied thereto;

55 Fig. 3 is a view in vertical section of the welt of a stocking showing how the tensioning means is incorporated therein.

Referring now to the drawing, the reference numeral 10 indicates generally the leg of a stocking having a turned-over welt 11, the edge of which is knit-in to the body of the stocking along the line 12 as indicated in Figures 2 and 3. Incorporated in the welt so as to be freely movable with respect thereto is an elastic band 13, serving 60 as a tensioning means to firmly hold the top of the stocking against the leg of the wearer and prevent the same from slipping downwardly. As shown in Figure 2, the elastic band 13 extends only a portion of the way around the circumference of the welt, the ends of the band being anchored to the welt respectively as by stitching at points 14 and 15. Preferably, the elastic should extend only around the bony front portion of the leg and terminate short of the fleshy rear 70 portion. It will be understood, however, that the

elastic may be otherwise positioned in the welt, and extend around as much of the circumference of the leg as may be desired.

An inelastic tape or strap, preferably comprising 80 separable members 16 and 17, extends around that portion of the circumference of the welt not occupied by the elastic band, the outer ends of the same being anchored to the welt, preferably at or near points 14 and 15 where the ends of the elastic terminate. For convenience and to prevent irritation of the leg such strap may be positioned on the outside of the welt. With such an arrangement, it will be seen that the tape will reinforce the welt of the stocking so as to prevent stretching thereof due to tensioning of the elastic band. To enable the proper tensioning 85 of the elastic suitable for the particular circumference of the leg of the wearer whereby the stocking may be held in position without undue pressure, an adjustable member 18 adapted to slide on one member of the tape reinforcing means is provided, said member 18 being further provided with a pin adapted to engage a clasp 19 associated with the other portion of the tape. The length of the tape may thus be conveniently adjusted by 90 moving the member 18 on the tape to effect the proper tensioning in the elastic band, and the clasp elements may be readily disengaged to allow 95 the stocking to be pulled on or off.

As shown in Figure 1, the leg 10 of the stocking 105 is longer than is the usual practice, the length being such as to bring the supporting means above or opposite to the smaller part of the leg above the largest portion of the calf. With such an arrangement very little tensioning in the elastic 110 band is required to prevent the stocking from sliding downwardly.

While I have here described and illustrated the application of my supporting means in connection with men's socks, it will be understood that it 115 may be equally well applied to children's stockings and socks and women's hosiery with the same advantages. It is true, of course, that the length of men's, women's and children's hosiery varies so that the tops of the same will occupy a 120 different position relative to the leg. My supporting means will operate efficiently in various positions relative to the stocking and leg of the wearer, and for this reason it is not entirely necessary that it be positioned in a welt at the top, 125 it being understood that the basic features of my supporting means comprise a tensioning band extending for a portion of the stocking circumference and an adjustable inelastic band extending 130 around the remainder of the circumference.

What I claim is:

1. In combination with a stocking leg, a circumferentially-extending supporting means, entirely encircling the same, said means being elastic for only a portion of its length and secured to the 135 stocking fabric at the ends of such portions so that the band will effect a tension over a restricted part of the circumference of the stocking leg.

2. In combination with a stocking leg, an independently formed circumferentially-extending 140 supporting means entirely encircling the same, said supporting means including an elastic band extending only part way around the stocking and secured to other portions of the supporting means and to the stocking at its ends, so that the band 145 will effect a tension over a restricted part of the circumference of the stocking leg.

3. In combination with a stocking leg, independently formed supporting means completely 150 encircling the same and comprising an elastic

- tensioning band extending around a portion of the circumference of the leg of the stocking and anchored at its ends thereto, and an inelastic reinforcing band connecting with the elastic band 5 and extending around the remainder of the circumference, said inelastic band being of such length as to prevent strain on the stocking fabric due to tension exerted by the elastic band.
4. In combination with a stocking leg, an elastic tensioning band extending around a portion of the circumference of the leg of the stocking and anchored at its ends thereto, and an inelastic band having its ends secured to the leg at the 10 points of termination of the elastic band extending around the remainder of the circumference and being of a length such as to prevent strain on the stocking fabric due to tension exerted by the elastic band, and means for adjusting the tension exerted by the elastic band.
5. A stocking having a double welt, an elastic tensioning band within said welt and extending for a portion of the circumference of the welt, and an inelastic band anchored at its ends to the 15 ends of the elastic band extending around the remainder of the circumference of the welt and secured to the welt so as to prevent stretch of the portion of the welt for which it extends by the elastic band, the elastic band being so positioned and of such length as to operate against the front bony part of a human leg and the inelastic band being adapted to bear against the rear fleshy portion of the same.
6. In combination with a stocking leg, a circumferentially-extending supporting means entirely encircling the same, said means being elastic for only a portion of its length and secured to the stocking fabric at the ends of such portion so that the band will effect a tension over a restricted part of the circumference of the stocking leg, and 20 means for adjusting the tension exerted by the elastic portion of the band.
7. In combination with a stocking leg, a circumferentially-extending supporting band encircling the same elastic for only a portion of its 25 length and secured to the stocking fabric at the ends of the portion so that the band will effect a tension over a restricted part of the circumference of the stocking leg, and adjusting means positioned away from the elastic portion to adjust 30 the tension exerted by the elastic portion.
8. In combination with a stocking leg, a cir-
- cumferentially-extending supporting means entirely encircling the same, said supporting means including an elastic band extending only part way around the stocking and secured to other portions of the supporting means and to the stocking at its ends, so that the band will effect a tension over a restricted part of the circumference of the stocking leg, and means for adjusting the tension exerted by the elastic portion of the band. 80
9. A stocking having a top, an elastic band portion of greater resiliency than the stocking fabric extending around the top for a part of its circumferential extent, and an inelastic band portion forming a continuation of the elastic band portion and providing therewith a continuous band extending around the full circumference of the top, said inelastic band portion having connection with both the stocking top and the elastic band portion. 85
10. A stocking having a top and supporting means for the stocking in the form of a band extending around the full circumference of the top, said band being connected to the top and including an inelastic portion and an elastic portion of greater resiliency than the stocking fabric, the 90 elastic and inelastic band portions being interconnected and each extending for a substantial part of the full circumference of the top.
11. A stocking having a top, an elastic band of greater resiliency than the stocking fabric extending part way around the top, and an inelastic band extending around the remaining part of the top connected to the top and to the ends of the elastic band. 105
12. A stocking having a leg portion terminating in a top and of such length that the top will extend above the large calf portion of the human leg and supporting means for the stocking in the form of a band extending circumferentially around the top above the calf, said band including an inelastic portion extending for a substantial distance around the circumference and secured to the top so as to prevent stretch in the portion of the top fabric which it overlies, said band also including an elastic portion of greater 110 resiliency than the stocking fabric, connecting with the inelastic portion as a continuation thereof and extending for the remaining distance around the top. 115
13. A stocking having a leg portion terminating in a top and of such length that the top will extend above the large calf portion of the human leg and supporting means for the stocking in the form of a band extending circumferentially around the top above the calf, said band including an inelastic portion extending for a substantial distance around the circumference and secured to the top so as to prevent stretch in the portion of the top fabric which it overlies, said band also including an elastic portion of greater 120 resiliency than the stocking fabric, connecting with the inelastic portion as a continuation thereof and extending for the remaining distance around the top. 120
